SAMUEL BERGSTEIN, OF MIDDLETOWN, OHIO, ASSIGNOR TO THE INTERSTATE FOLDING
BOX COMPANY, OF MIDDLETOWN, OHIO

PAPER BOX OR THE LIKE

Application filed May 31, 1928. Serial No. 282,018.

This invention relates to improvements in paper boxes, having particular reference to boxes adapted to be arranged for displaying their contents.

The manufacturer's profit in paper boxes is generally so small that savings in the character and amount of raw material used, and in time and labor costs in manufacturing the boxes is vitally important. Any possible profits can be made only by giving strict attention to these factors of production.

The objects attained in the present invention consist in a paper box of novel construction in which the amount of material required is reduced to the minimum without weakening the structure of the box; in which box board finished on one face only may be used without impairing the quality of the box for appearance; in which all printing for both the lid and body of the box is on the same face of the paper, and in which the opposite sections are arranged in a novel manner one relative to the other for displaying the contents of the box.

The novel construction consists in assembling the opposite sections of the box inversely one relative to the other, the finished side of the material being turned inward in one section and outward in the other section, and the joints of the section that has the finished side of the material turned inward being formed outward and of the other section inward. As the box is arranged for displaying the contents, the section that is finished inward is placed telescopically in the section that is finished outward thus presenting finished faces both inward and outward, the inner section being adapted to be raised at one end and supported frictionally at an angle in the outer section for displaying the contents to better advantage.

In the accompanying drawings which serve for illustrating the invention as practiced with one type of box:

Figs. 1 and 2 are views of the blanks for the opposite sections of the box, illustrating the manner of cutting the blanks from the sheets for minimizing the waste of material;

Fig. 3 is a sectional view of the outer section of the box;

Fig. 4 is a sectional view of the inner section of the box;

Fig. 5 is a view of the box assembled one section with the other;

Fig. 6 is a view of the box arranged telescopically one section with the other for displaying the contents. 55

The box blank as shown in Fig. 1 for the outer section of the box consists of the top portion 1, sides 2, ends 3, end corner flaps 4, 60 and reinforcing sealing flaps 5, and corner reinforcing sealing flaps 6.

The blank for the inner section of the box consists of the bottom portion 7, sides 8, ends 9, end corner flaps 10, corner reinforcing sealing flaps 11 and advertisement tab 12. 65

As shown in Fig. 3 the outer section of the box has the finished side of the material turned outward, the section being formed by folding the sealing strips 5 over the upper 70 edges of the end flaps 4 and securing the same adhesively to the inner face of flaps 4, the flaps 6 being joined in like manner to the inner faces of the side walls 2, thus serving to reinforce the end and corner constructions. 75

The inner section of the box, as shown in Fig. 4 has the finished side of the material turned inward, the section being formed by joining the end corner flaps 10 outwardly over the end walls 9, the corner reinforcing flaps 11 being joined to the inner faces of the side walls 8 thus serving to reinforce the corners. When the box sections are assembled one with the other, the advertisement tab 12 is extended flat over the contents of the box, 85 the flap being self-sustaining in raised position as the box is arranged for displaying the contents.

It will be apparent that the box arranged for displaying the contents, as shown in Fig. 6, will present the finished side of the paper on all exposed inward and outward faces, except the small portion of the inner section raised above the upper edge of the outer section; also that the faces of both sections 95 broken by seams or joints will not be exposed, thus having the effect in a cheaply constructed box of presenting only finished unmarred surfaces on all exposed faces, the improved box being equal, even superior in 100

this respect to boxes made of box board finished on both faces and of more costly construction. All printing also will be on one side only of the material for both sections of the box. Any printing on the face 1 of the outer section of the box will apply to the box or contents as the box is closed with face 1 turned upward. As the box is arranged for displaying its contents, face 10 will be at the bottom of the box.

It will be apparent that variously constructed boxes can be constructed and arranged in the manner herein described having particular reference to the inverse arrangement of the finished side of the paper in the opposite sections of the box, and the inverse formation of the joints in one section of the box for the purposes herein set forth to which the invention relates irrespective of other structural features of the box.

I claim as my invention:

1. A paper box consisting of opposite sections arranged telescopically one of the other, each constructed of material finished 25 on one side only, the outer section having the finished side of the material turned outward, the inner section having the finished side of the material turned inward, and the inner section having its joints formed outwardly, inverse to the formation of the joints of the outer section thereby presenting unbroken inner faces of said section, said sections being adapted as the box is arranged for displaying its contents for placing the inner section into the outer section for presenting the finished side of the material inside and outside the box with faces of both sections broken by joints unexposed.

40 2. A paper box consisting of opposite sections arranged telescopically one of the other, each constructed of material finished on one side only, one of said sections having the finished and printed side of the material turned outward and the other section having the finished side turned inward, said sections being adapted as the box is arranged for displaying its contents for placing one section into the other section thus presenting finished faces of the material inwardly and outwardly with the unfinished faces of the material disposed oppositely one of another and concealed.

55 In testimony whereof, I affix my signature.

SAMUEL BERGSTEIN.
